UNITED STATES PATENT OFFICE.

JOHN MOTE, OF ANTWERP, OHIO.

SAW-MILL DOG.

SPECIFICATION forming part of Letters Patent No. 252,496, dated January 17, 1882.

Application filed September 5, 1881. (No model.)

To all whom it may concern:

Be it known that I, JOHN MOTE, a citizen of the United States, residing at Antwerp, county of Paulding, in the State of Ohio, have invented certain new and useful Improvements in Dog Attachments for Saw-Mills; and I do hereby declare the following to be a full, clear, and exact description of the invention, such as will enable others skilled in the art to which it appertains to make and use the same, reference being had to the accompanying drawings, and to letters of reference marked thereon, which form part of this specification.

My invention relates to dog attachments for saw-mills.

The object and nature of the invention will be more fully set forth in the specification, and the novelty pointed out in the claims.

In the drawings, Figure 1 represents a perspective view of my attachment; Fig. 2, detail views, and Fig. 3 a modified form of the device.

A represents a frame, which consists of back bar, A', cross-pieces I K, bar C, and bearing-bar B, and having box or sleeve F, a lever, D, dog E, and binder or cam H attached thereto, as will hereinafter be described. The frame A is made of any suitable material, but preferably of iron, and is attached by bar A' to the head-block in any suitable manner. The inner bar, B, and outer bar, C, are provided with a box or sleeve, F, the opening of which is large enough to allow the box to be moved up or down upon the bars. This box is provided with bearings or rollers G G, which are free to turn upon their seats, and have a squared opening, through which the square shaft E' of dog E is inserted. This shaft may be of any desired length, but is preferably made sufficiently long to allow the fang to be drawn over the bed a sufficient distance to grasp a log of the largest diameter. The shaft is bent at right angles near the fang end, as shown, so that when the dog has been turned upwardly the point of the fang will be upon the same level as the elbow. The object of this is to give the fang a greater sweep, so that in falling it will be forced deeply into the log. Upon this shaft, between the longitudinal sides

of box F, is placed a binder or cam, H, which turns with the shaft. This binder is a cylinder, having a longitudinal slice or segment removed from its periphery to give it a cam-like form, so that when the rounded part is turned toward the bearing-bar the pressure will be greater than when the flat face is opposite the bearing-bar B. A spring, e, is placed upon the inner side of one end of the sleeve F and presses against the rear side of bar B, and tends to draw the binder against the bearing-bar. The pressure of this spring, however, is only enough to hold the flat face of binder H against the bearing-bar without interfering with its up or down movement when worked by the operator. If it be desired to clamp the sleeve at any particular point, the rounded part of the binder is turned against the bearing-face. This is accomplished by depressing lever D, which is attached to shaft E' by means of squared openings in its bifurcated arms. The operation is as follows: Lever D is elevated to bring the flat face of binder H opposite the bearing-bar, so that box or sleeve F could be elevated to allow the log to pass under the dog. The dog is then adjusted to its place by moving shaft E' in rollers G until the right point is reached for the insertion of the fang. The box is now lowered until the fang is nearly in contact with the log. Lever D is depressed and turns the rounded part of binder H against the bearing-face, and at the same time forces the fang into the log. When the log has been sawed the lever is elevated, the fang is withdrawn, and the device ready for another log.

If desired, a second box F, carrying a horizontally-adjustable dog, E'', and capable of being adjusted vertically, may be attached to the bottom of the frame.

In Fig. 3 a rack and mangled pinion are shown in lieu of the bearing-face and binder. The cogs in the pinion correspond to the rounded part of the binder and the mangled part to the flat face. The operation of this device is similar to that shown in Fig. 1.

What I claim as new is—
1. The combination of a saw-dog with a box arranged substantially as shown, a breaking attachment fixed upon the shaft of the dog

and in contact with a bearing-bar, and a spring located between the box and rear of the bearing-bar, for the purpose set forth.

2. A saw-dog located upon the lower side of a frame for grasping the under side of a log, in combination with a second saw-dog having a breaking attachment upon its shaft and mounted upon a box sliding upon said frame,

and provided with a spring for holding the breaking attachment against a bearing-bar, substantially as described.

JOHN MOTE.
